[57] CLAIM

The ornamental design for a planar card flashlight, as shown
and described.

DESCRIPTION

FIG. 1 is a front perspective view of a planar card flashlight
showing my new design, the broken lines showing the user's
hand, attachment slot, and light beam are for illustrative
purposes only, and form no part of the claimed design;
FIG. 2 is a front plan view of my design;
FIG. 3 is a top elevational view thereof;
FIG. 4 is a side elevational view thereof, with the opposite
side being a mirror image;
FIG. 5 is a bottom elevational view thereof;
FIG. 6 is a rear plan view thereof;
FIG. 7 is a front plan view of a second embodiment of the
planar card flashlight assembly of FIG. 1;
FIG. 8 is a top elevational view of the second depicted
embodiment thereof;
FIG. 9 is a side elevational view of the second depicted
embodiment thereof, with the opposite side being a mirror
image;
FIG. 10 is a bottom elevational view the second depicted
embodiment thereof;
FIG. 11 is a rear plan view of the second depicted embodiment
thereof;
FIG. 12 is a front plan view of a third embodiment of the
planar card flashlight assembly of FIG. 1;
FIG. 13 is a top elevational view of the third depicted
embodiment thereof;
FIG. 14 is a side elevational view of the third depicted
embodiment thereof, with the opposite side being a mirror
image;
